CLAIM

The ornamental design for a smart watch, as shown and described.

DESCRIPTION

FIG. 1 is a top, front, and right perspective view of a first embodiment of the smart watch showing our new design.

FIG. 2 is a front view of the smart watch of FIG. 1.

FIG. 3 is a rear view of the smart watch of FIG. 1.

FIG. 4 is a right side view of the smart watch of FIG. 1.

FIG. 5 is a left side view of the smart watch of FIG. 1.

FIG. 6 is a top view of the smart watch of FIG. 1.

FIG. 7 is a bottom view of the smart watch of FIG. 1.

FIG. 8 is a top, front, and right perspective view of a second embodiment of the smart watch.

FIG. 9 is a front view of the smart watch of FIG. 8.

FIG. 10 is a rear view of the smart watch of FIG. 8.

FIG. 11 is a right side view of the smart watch of FIG. 8.

FIG. 12 is a left side view of the smart watch of FIG. 8.

FIG. 13 is a top view of the smart watch of FIG. 8; and,

FIG. 14 is a bottom view of the smart watch of FIG. 8.

The broken lines in the drawings illustrate portions of the smart watch that form no part of the claimed design.

1 Claim, 6 Drawing Sheets
